UNITED STATES PATENT OFFICE.

HENRY B. LITTLEFIELD, OF CLEVELAND HEIGHTS, OHIO.

APARTMENT WITH DISAPPEARING BED.

Application filed April 3, 1922. Serial No. 549,008.

To all whom it may concern:

Be it known that I, HENRY B. LITTLEFIELD, a citizen of the United States, and a resident of Cleveland Heights, county of 5 Cuyahoga, and State of Ohio, have invented a new and useful Improvement in Apartments with Disappearing Beds, of which the following is a specification, the principle of the invention being herein explained 10 and the best mode in which I have contemplated applying that principle, so as to distinguish it from other inventions.

The present invention relates to house and bed construction whereby two beds may be 15 stored one above the other, so that one of the beds may be brought out into a room other than in which it is stored. The construction of the floors and walls and of the beds is of particular interest as well as the 20 means for closing the necessary wall and floor openings. The present type of bed arrangement is particularly adaptable to small apartments where there is but a single bedroom adjacent a living room or the like 25 where a second bed may be advantageously used but where it is undesirable to store the same. To the accomplishment of the foregoing and related ends, said invention, then, 30 consists of the means hereinafter fully described and particularly pointed out in the claims.

The annexed drawing and the following description set forth in detail certain mechanism embodying the invention, such 35 closed means constituting, however, but one of various mechanical forms in which the principle of the invention may be used.

In said annexed drawing:—

Fig. 1 is a sectional view through two 40 rooms showing the arrangement of the beds and tracks; Fig. 2 is a sectional view through the bed and floor when the bed is in position in the second room, taken on the line 2—2 of Fig. 1; Fig. 3 is a sectional view on the 45 line 3—3 of Fig. 1; Fig. 4 is a perspective view of the wall, floor and beds with parts in section; and Fig. 5 is a perspective view of the floor and wall arrangements with the beds removed.

As best illustrated in Fig. 1, the present 50 arrangement makes use of two rooms with a wall 1, the floor 2 of the normal bedroom or sleeping porch being raised above the level of the floor 3 of the room where an extra bed is desirable for use but in which the bed will not be stored. In the room or

porch where the beds will be kept, the floor is cut away to form a storage space 4 which is provided with trackways 5 at each side. Around the edge of the sunken floor portion 60 is placed an angle iron 6 or other raised strip and the usual bed 7 is mounted on legs 8 provided with casters or the like, the legs being spaced so that the casters will pass by the flanges thus preventing the bed 65 from accidentally dropping down into the storage space.

In the wall between the two rooms an opening 10 is provided which may of course be closed by any desirable type of sliding 70 panels, doors or the like, and there are trackways 11 in the second room which are continuations of the trackways 5 in the bedroom. A second bed 12 is provided which is sufficiently narrower than the bed 7 so 75 that it will pass between the legs of the same, and the head 13 and foot 14 of the bed are low so that the bed 12 may slide under the first bed 7.

These trackways 5 and 11 are continuous 80 and the trackways 11 gradually rise to the floor level. At about the center point of each trackway 11 there is mounted a hinged track strip 15 which may be lifted after the bed is moved past the same and locked with 85 its free end 16 in position with the floor level by means of a sliding bolt 17 set in the floor, so that the bed may be rolled back up these inclined strips to the floor level. To close the trackways for the normal use of the room, the trackways are provided at the top with a wider portion forming a horizontal shoulder 18 around the trackway which is of a depth to receive a closure strip or board 19 painted or finished 90 to match the remainder of the floor.

In returning the bed 12 to its daytime position it is rolled down the strip 15 and the strip is then released by withdrawing the bolt, after which the bed may be moved 100 along the trackways through the wall opening to its position under the bed 7.

By the present arrangement, any desired type of mattress may be used as it is not clamped or secured to the bed in any way 105 and the storage space needed is only that of a single bed, except for the trackways and open space under the bed 5. No unsightly large door or wall space is used and the opening in the wall does not need to exceed 110 about 18 inches in height. Where the bedroom is large the bed 7 may be moved away

from the extra bed 12 during the daytime so that both beds may be aired. If desired, both bed may be used in the sleeping room, the upper bed being moved away to allow 5 the lower one to be used.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

15 1. In building construction for apartments with disappearing beds, the combination with two adjacent rooms separated by a wall having an opening at the bottom, a recess in the floor of one room having 20 trackways adjacent the sides of the recess, and trackways formed in the floor of the adjacent room and being continuous with such first mentioned trackways.

25 2. In building construction for apartments with disappearing beds, the combination with two adjacent rooms separated by a wall having an opening at the bottom, one of said rooms having a floor level higher than the other, a recess in the floor of said 30 room of higher level, such recess being adjacent such wall opening, trackways in the floor at the sides of such floor recess, other trackways in the second room floor communicating with such first mentioned trackways and inclining up to floor level for a 35 portion of their extent.

3. In building construction for apartments with disappearing beds, the combination with two adjacent rooms separated by 40 a wall having an opening at the bottom, one of said rooms having a floor level higher than the other, a recess in the floor of said room of higher level, such recess being adjacent such wall opening, trackways in the 45 floor at the sides of such floor recess, other trackways in the second room floor communicating with such first mentioned trackways and inclining up to floor level for a

portion of their extent and removable means for normally closing such second trackways.

4. In building construction for apartments with disappearing beds, the combination with two adjacent rooms separated by a wall having an opening at the bottom, 55 one of said rooms having a floor level higher than the other, a recess in the floor of said room of higher level, such recess being adjacent such wall opening, trackways in the floor at the sides of such floor recess, other 60 trackways in the second room floor communicating with such first mentioned trackways and inclining up to floor level for a portion of their extent, and strips pivotally mounted in such second trackways and extending toward said wall, said strips being adapted to be raised and locked in position to form inclined guide-ways up which the bed may be rolled to bring it completely to 65 floor level.

70 5. In building construction for apartments with disappearing beds, the combination with two adjacent rooms separated by a wall having an opening at the bottom, one of said rooms having a floor level higher 75 than the other, a recess in the floor of said room of higher level, such recess being adjacent such wall opening, trackways in the floor at the sides of such floor recess, other trackways in the second room floor communicating with such first mentioned trackways and inclining up to floor level for a 80 portion of their extent, and strips pivotally mounted in such second trackways and extending toward said wall, said strips being 85 adapted to be raised and locked in position to form inclined guide-ways up which the bed may be rolled to bring it completely to floor level, and locking bolts mounted in the 90 floor of said room of lower level and adapted to be moved under said pivoted strips to maintain the same in their raised position.

Signed by me, this 31st day of March, 1922.

HENRY B. LITTLEFIELD.
